POLISHING FILE

James B. Whitlock, Reseda, Calif.

Application May 22, 1957, Serial No. 660,893

12 Claims. (Cl. 51—187)

This invention relates to hand files and more particularly to an improved hand polishing file featuring means for clamping readily replaceable strips of abrasive material in place together with means for tensioning such strips as found most suitable for the work at hand.

There has been proposed heretofore hand files having means by which replaceable strips of abrasive material may be clamped to a suitable holder. However, devices of this type as heretofore provided have serious shortcomings and disadvantages obviated by this invention. For example, the means provided in prior files for securing the opposite ends of the abrasive strips to the holder and for thereafter tensioning the strips are complex in construction, difficult for the novice to use and the strip-clamping arrangements are unreliable.

The construction provided by the present invention satisfactorily overcomes the foregoing and other disadvantages of prior files in an unusually satisfactory manner. The elongated main body of the holder is provided with a simple self-gripping clamp at one end which acts to clamp the adjacent ends of the two strips to the holder. The combined strip clamp and the strip tensioning means provided at the rear end of the holder comprises a single operating handle serving normally as the handle for the holder and operating by rotation in opposite directions about its own axis to release or to tension the two strips simultaneously depending on the direction in which the handle is rotated. Featured is a spring which automatically increases the gripping action on the strips as the tension is increased. Additionally, the single clamping member at the remote end of the holder acts automatically to increase its gripping action as the tension is increased on the abrasive strips.

Accordingly, it is a primary object of this invention to provide an improved polishing file having simple means for replaceably clamping one or more strips of abrasive material therein.

Another object of the invention is the provision of a hand held polishing file having a simple easily operated clamp at its end for detachably clamping one or more strips of replaceable abrasive material to the holder, one of the clamps being effective to tension the strips of abrasive material.

Another object of the invention is the provision of a polishing file which can be assembled from simple, inexpensive and easily manufactured components without need for jigs, dies and other special manufacturing facilities.

These and other more specific objects will appear upon reading the following specification and claims and upon considering in connection therewith the attached drawing to which they relate.

Referring now to the drawing in which a preferred embodiment of the invention is illustrated.

Figure 1 is a side elevational view from one edge of a file embodying the present invention;

Figure 2 is an enlarged central longitudinal sectional view taken on line 2—2 of Figure 1;

2

Figure 3 is an enlarged fragmentary view similar to Figure 1 showing the clamp at the handle end of the holder released for the replacement of the abrasive strips.

- Referring to Figures 1-3 there is shown a polishing file 5 designated generally 10 having a main body 11 with flat opposite sides of a suitable width depending upon the use to which the file is to be put. This body may be formed of wood, plastic or of lightweight metal. The clamping facility provided at the forward end preferably comprises 10 a slot extending crosswise of the main body and having the configuration best shown in Figure 1 and including a narrow portion 12 opening into a wide based portion 13 the opposite side walls 14, 14 of which converge toward the relatively narrow mouth 15. Seated within narrow portion 12 is a strip of soft rubber or other elastic material 16 the forward end of which terminates close to the plane of mouth 15 and having sufficient clearance from sides 14 as to permit the insertion of the ends of abrasive strips therewith. A suitable keeper 17 conveniently provided by a round wooden dowel pin 17 has a diameter appreciably greater than the width of mouth 15 and resiliently urged toward this mouth by elastic strip 16. As is shown in Figure 2, keeper 17 has a length corresponding to the width of main body 11 so that its ends do not 20 project beyond the edges of the main body yet are conveniently accessible to the tips of the user's thumb and index finger so that pressure can be applied to the opposite ends when compressing strip 16 sufficiently to permit the withdrawal and insertion of the ends of the abrasive strips.
- The releasable clamping means provided at the rear end of main body 11 comprises a handle grip 20 having a central bore 21 loosely receiving a long bolt 22 the threaded forward end of which is threaded into a bore 24 30 opening through the adjacent end of the main body. A threaded thimble 25 surrounds the body of bolt 22 and has one end fixedly threaded into the forward end of the hand grip, a strong adhesive preferably being applied to the mating threads of the thimble and of the hand grip to prevent unthreading of these components. It will be understood that bolt 22 likewise has a tight fit with threaded bore 24 and is turned into this bore until the forward end of sleeve 25 bears lightly against end wall 26 of the main body, a washer or suitable low friction 40 device being inserted if desired between surface 26 and the end of thimble 25. Accordingly, it will be understood that hand grip 20 and sleeve 25 are free to rotate about the stationary mandrel or support provided by the body of bolt 22.
- The clamping device for the adjacent ends of the abrasive strips comprises a pair of flat jaws or plates 28 and 29 having their facing surfaces lying close together and forming the abrasive gripping surfaces of the clamp. The threaded opening centrally of jaw plate 28 mates with the 50 threads on sleeve 25, whereas outer plate 29 has a slightly larger smooth opening 30 slidably freely along sleeve 25. A stiff compression spring 31 encircles sleeve 25 with one end bearing against plate 29 and the other end bearing against a washer 32 at the forward end of hand grip 20.
- Suitable means are provided for preventing the clamping plates 28 and 29 from rotating as sleeve 25 is turned, as, for example, a pair of guide pins extending loosely 60 through aligned openings 34 in plates 28 and 29, these pins being anchored in recesses 35 in the main body of the file. While a pair of guide pins 33 are here shown and are preferred, it will be appreciated that a single pin may be used.
- Strips of abrasive material 37 and 38 are shown as mounted along the opposite sides of main body 11. Such 70 strips may have either a paper or a fabric backing and a face covering of abrasive powder or grit secured thereto by a suitable bonding agent. These strips have a width

corresponding to that of the main body and a length somewhat longer than the main body in order that their opposite ends may be overturned and engaged in the described clamping means. In a preferred arrangement abrasive strips having different sized grit are mounted on the opposite sides of the holder, as for example a relatively fine grade grit for strip 37 and a much coarser grade grit for strip 38 to the end that the user may perform a coarse filing with one strip and fine polish grinding with the second strip merely by reversing the position of the file with respect to the surface being finished.

The manner in which the abrasive strips are mounted will be quite apparent from the foregoing description of the file construction. Two strips 37 and 38 of abrasive material are cut to suitable equal lengths and the opposite ends are folded over or sharply creased transversely of the strips as along transverse lines 39 and 40, these two crease lines being equally spaced apart longitudinally of the strips. Hand grip 29 is rotated in a direction to thread plate 28 toward the rear end of the main body thereby relaxing the compressive forces acting on spring 31. In this position, the rear ends of the strips may be readily withdrawn from the clamping plates.

The forward ends of the strips are released by grasping the end of keeper dowel 17 between the thumb and forefinger and pulling it backwardly compressing elastic strip 16 thereby releasing the forward ends of the abrasive strips from groove 13. Dowel pin 17 is similarly held retracted while the creased tabs of a pair of new abrasive strips are inserted against the side walls 14 of clamping groove 13. When properly positioned against walls 14, the dowel is released allowing rubber strip 16 to press the dowel toward the mouth 15 of the groove thereby wedging the strips firmly against the groove side walls.

The turned over rear ends of strips 37, 38 are then fitted between clamping plates 28 and 29 and held in place therein by light finger pressure as hand grip 20 is rotated to thread plate 28 along sleeve 26 toward the hand grip as spring 31 is compressed to force plate 29 into firm gripping contact with the strip ends. Further rotation of the hand grip increases both the clamping pressure on the strip ends as well as the tension on the strips, the rotation of the grip being discontinued when the strips are at a desired tautness. The file is now ready for use and may be employed in the usual manner to abrade and then polish surfaces of metal, wood, plastic or the like.

While the particular hand polishing file herein shown and disclosed in detail is fully capable of attaining the objects and providing the advantages hereinbefore stated, it is to be understood that it is merely illustrative of the presently preferred embodiments of the invention and that no limitations are intended to the details of construction or design herein shown other than as defined in the appended claims.

I claim:

1. A hand file adapted for use with replaceable strips of abrasive material, said file comprising a rigid backing member having a hand grip rigidly and adjustably secured to one end thereof, means at the opposite ends of said rigid member for releasably clamping the opposite ends of a strip of abrasive material therein, and means operable by rotation of said hand grip independently of said clamping means for adjusting the tension on said strip of abrasive material longitudinally thereof.

2. A hand file as defined in claim 1 including a plurality of strips of abrasive material releasably supported along the opposite flat surfaces of said rigid member, each adapted to be tensioned simultaneously by the adjustment of said hand grip.

3. A hand file as defined in claim 1 wherein the means for holding said abrasive strip to the forward end of said rigid member comprises a groove across the end of said member, and self-clamping resiliently backed means seated

in said groove operable to clamp the end of an abrasive strip releasably in place in said groove.

4. A hand file adapted to support a pair of abrasive strips stretched taut flat against an elongated rigid backing member, said backing member having wide flat surfaces on the opposite sides thereof, a groove across one end of said backing member having side walls converging toward the entrance end thereof, a clamping member loosely supported lengthwise of said groove and having a width greater than the mouth of said groove, resilient means urging said clamping member toward the mouth of the groove and being effective in cooperation with said clamping member to clamp the ends of abrasive strips against the side walls of said groove, and means at the opposite end of said backing member for clamping and tensioning the opposite ends of strips of abrasive material extending along the flat sides of the backing member.

5. A hand file as defined in claim 4 wherein said means for tensioning strips of abrasive material includes a hand grip rotatably secured to the end of said backing member, and means controlled by the rotation of said hand grip in one direction to tension strips of abrasive anchored to the grooved end of said backing member and operable to slacken said abrasive strips when rotated in the opposite direction.

6. A hand file for use with replaceable strips of flexible abrasive material, said file comprising a long flat backing member having a narrow mouthed groove across one end, said groove being adapted to seat the ends of abrasive material, resilient self-locking means manually depressible to receive the ends of abrasive strips and for automatically clamping the same in place in said groove, a hand grip rotatably supported at the other end of said backing member, resilient clamping means operatively associated with said hand grip for clamping the adjacent ends of abrasive strips, said hand grip being rotatable to effect displacement of said clamping means relative to said backing member to tension said strips lengthwise of said backing member when rotated in one direction and to relax the tension on said strips when rotated in the reverse direction.

7. A hand file as defined in claim 6, said resilient clamping means including a pair of clamping plates, threaded means rotatable with said hand grip and passing freely through one plate into threaded engagement with the other plate, and spring means interposed between said hand grip and said one plate for urging said plates together.

8. A hand file as defined in claim 7 including guide pin means anchored to the end portion of said backing member and extending through openings in said plates laterally offset from said threaded means and parallel thereto.

9. A hand file for detachably clamping a flexible strip of abrasive material stretched taut along an elongated backing member, a handle mounted at one end of said member and rotatable about its longitudinal axis, a threaded sleeve fixed to said handle and having its end rotatably supported adjacent the handle end of said backing member, a pair of clamping plates mounted on said sleeve one plate having threaded engagement with said sleeve and the other being loosely journaled thereon, and spring means urging said loosely journaled plate against the other plate to grip tightly one end of an abrasive strip extending along said backing member.

10. A hand file as defined in claim 9 including stationary guide means fixed to said backing member and extending through guide passage means on said plates to hold the same against rotation with said sleeve and said handle as the latter are rotated to tension and slacken an abrasive strip, said guide means having one end anchored to said backing member.

11. A hand file for detachably supporting a flexible strip of abrasive material stretched taut along the flat surface of a backing member, said backing member having clamping and adjustable tensioning means at one end thereof adapted to grip firmly one end of an abrasive

strip, and means for releasably anchoring the strip to the opposite end of the backing member, said anchoring means including a groove across the end of backing member, the side walls of said groove converging to a narrow mouth, a keeper extending along said groove and freely movable therein but having a width greater than the mouth portion of said groove, and resilient means urging said keeper toward said groove mouth and effective in cooperation with said keeper to wedge the end of an abrasive strip between said keeper and one wall of said groove.

12. A hand file as defined in claim 11 wherein said backing member has a pair of flat surfaces along the opposite sides thereof and parallel to the longer axis of said

groove, said keeper being effective to anchor the adjacent ends of a pair of abrasive strips in said groove and against the opposed side walls thereof, said clamping and tensioning means being operable to clamp the other ends of said strips and to tension said strips simultaneously.
